PROTECTIVE SYSTEM

Robert R. Goodrich, Camden, N. J., assignor to
 Radio Corporation of America, a corporation
 of Delaware

Application May 19, 1934, Serial No. 726,442

6 Claims. (CL 250—27)

My invention relates to protective systems and more particularly to systems for protecting cathode-ray tubes against destructive beam-current.

When cathode-ray tubes are utilized in television receivers or for the purpose of alternating current analysis and the like, it is customary to provide ray-deflecting devices which cause the ray, or beam to periodically traverse the fluorescent screen in a pre-determined pattern. 5 If, by reason of failure of the ray-deflecting devices, etc., the ray comes to rest upon the fluorescent screen and remains stationary for even a very short time the screen is burned and the tube is rendered substantially useless for satisfactory picture reception.

It is, accordingly, an object of my present invention to provide means whereby failure of the ray-deflection generators associated with a cathode-ray tube does not occasion the flow of destructive beam current.

Another object of my invention is to provide 10 a protective system for a cathode-ray tube that shall function to prevent destructive beam-current in the event of breakage of certain essential circuit connections.

A still further and more specific object of my invention is to provide a protective system for a cathode-ray tube that shall function to prevent destructive beam-current in the event that certain essential connections in the protective system, itself, are broken.

In accordance with my invention, I prefer to accomplish the foregoing objects by providing means for depriving the first anode, in a cathode-ray tube, of positive potential in the event that the ray ceases to be deflected according to a pre-determined pattern. Specifically, I provide a relay for connecting the second anode to ground and for simultaneously de-energizing the source which supplies it with potential and I make use of a unidirectional current derived from the ray-deflecting devices for determining the operation of the relay. In addition, I so interconnect the relay and the current-deriving means that failure of the latter also causes the relay to drop out, thus affording added protection.

The novel features that I consider characteristic of my invention are set forth with particularity in the appended claims. The invention itself, however, both as to its organization and its method of operation, together with additional objects and advantages thereof, will best be understood from the following description of a specific embodiment, when read in connection with the accompanying drawings, in which:

Figure 1 is a view of a portion of a television receiving system in which an embodiment of my invention is included, and

Fig. 2 is a view of a portion of a television receiver including an alternative embodiment of 5 my invention.

In both figures, like elements are similarly designated.

Referring now to Fig. 1 of the drawings, a cathode-ray tube 1 of the general type to which 10 my invention pertains is constituted by an evacuated envelope having a bulbous portion 3 and a cylindrical portion 5. The interior wall of the bulbous portion may be provided with a metallic coating 7 to serve as a second anode and the 15 large end is provided with an interior fluorescent screen 9 usually made from Willemite or the like. An electron gun, constituted by an equipotential cathode 11, a grid 13 and a first anode 14, is disposed in the cylindrical portion of the 20 tube. Suitable grid-cathode biasing potential and anode potential is provided from a common source, exemplified in the drawings by a bleeder resistor 15 connected across the output terminals of a rectifier 17, over a plurality of conductive connections 19, 21, 23 and 25 allocated, 25 respectively, to the grid, the cathode, the first anode and the second anode.

In order that a two-dimensional picture may be reproduced on the fluorescent screen, means 30 are provided for causing the ray to simultaneously traverse the screen in two directions normal to each other. In an actual commercial system ray-deflection may be accomplished by utilizing electromagnetic deflection coils alone, 35 electrostatic deflecting plates alone or by a combination of coils and plates.

In order to simplify the drawings I have exemplified the vertical deflecting system by a single coil 27 connected to the output terminals of 40 a ray-deflection impulse generator 29 and the horizontal deflecting system also by a single coil 31 connected to the output terminals of a ray-deflection impulse generator 33. It is to be understood, of course, that in the system as actually constructed each of the single coils is replaced by a pair of coils connected in series-aiding relation and disposed at opposite sides of the cylindrical portion of the tube.

The generators may be of the continuous oscillation type, merely synchronized by incoming synchronizing impulses, or they may be of the intermittent type which only functions to provide output impulses when triggered-off by the 50 55

synchronizing impulses. My invention, as will be apparent hereinafter, is applicable to either type.

If, during the operation of the system thus far described, for translating incoming picture-signals into a visual reproduction of the transmitted view, the deflecting generators should fail simultaneously the fluorescent screen in the tube would immediately be ruined. Even though but one of the generators should fail, or the connections between it and the deflecting coils should break, the screen might be spoiled since the ray, traversing the screen in a single direction under an accelerating potential of the order of 10,000 volts, causes much higher localized heating than normal.

In accordance with my invention, therefore, I provide means, responsive to de-energization of one or both of the deflecting coils, for depriving the ray of accelerating potential.

Referring once more to Fig. 1, it will be noted that the circuit for supplying the primary winding 35 of a power transformer 37 feeding the rectifier includes an armature 39 and a fixed contact 41 of a relay 43. It will also be noted that the relay is provided with a second grounded armature 45 which is connected to the cathode of the cathode-ray tube and is normally held away from a fixed contact 47 from which a connection 49 extends to the first anode 14 in the cathode-ray tube. The armatures are interconnected by an insulator 51 for simultaneous movement.

Obviously, when the relay is energized the armature is drawn up and held to complete the energizing circuit for the primary winding of the power transformer. When it drops out, the energizing circuit is broken and the first anode is connected directly to the cathode and to ground, thus depriving it of potential.

In order that the position of the armatures may be so controlled by the ray-deflecting impulses that they will drop out upon failure thereof, I connect the relay winding between the anode 13 of a thermionic device 54, hereinafter called the control tube, and the positive end of a bleeder resistor 55 connected across the terminals of a source 57 preferably of unidirectional potential such as a battery or rectifier but an alternating current source may be used. The cathode of the control tube is connected to an intermediate point on the bleeder resistor and a fixed or static negative bias sufficient to stop the flow of output current is provided by connecting the grid to the negative end of the resistor.

Since, in the operation of the system, the control tube must conduct current to energize the relay just so long as the ray-deflection coils are energized from the ray-deflection generators, I provide further means for deriving positive potentials from the deflection impulses and for utilizing them to nullify the fixed negative potential derived from the bleeder resistor.

Specifically, I prefer to include a plurality of resistors 59 and 61 in the input circuit of the control tube, between the grid and cathode thereof, and cause unidirectional currents derived from the ray-deflection impulses to flow therein when the system is in operation.

To provide a current proportional to the horizontal impulses I connect one of the resistors 59 between the cathode and anode of a diode rectifier 63, including in the circuit the secondary 5 of a transformer 67 the primary 69 of which is connected in series in the horizontal ray-de-

flection circuit. A similar diode 71 is connected across the other resistor 61 and it is fed from the vertical ray-deflection circuit through a similar transformer 73.

As will be clear from the drawing, the several diodes are so connected to the resistors that the rectified current flowing sets up potentials in opposition to the negative potential impressed upon the grid of the control tube from the potential supply resistor 55. Through proper choice of the constants of the system the static negative potential may be overcome and the grid of the control tube given the proper positive potential to permit just enough space current to flow in the relay winding to pull up and hold the armatures. After the proper balance has been obtained, if either or both diodes are deprived of input excitation the flow of space current in the control-tube is so reduced that the armatures drop and, as will be clearly apparent from the drawings, the first anode in the cathode-ray tube is immediately connected to ground and the rectifier supplying potential thereto is de-energized.

In order to provide a further measure of safety I prefer to utilize equipotential cathodes in the diodes and in the control tube and to energize them in parallel from a power transformer 75 the primary 77 of which is energized in parallel with the primary winding 35 of the power transformer 37 energizing the main rectifier 17. The failure of either diode cathode-heater, therefore, deprives the grid of the control-tube of a portion of the neutralizing potential, thus de-energizing the relay. Also, should the control-tube cathode-heater fail, the same action, obviously, takes place.

To prevent the relay from "chattering" I find it expedient to connect a reasonably large capacitor 79 in shunt with each of the diode-output-resistors. Each capacitor, for example, may have a capacity of .015 mfd., and each resistor may be .2 megohm. Further a reactor-condenser filter may be interposed between the output resistors 59 and 61 and the input terminals of the control-tube for the same purpose although such a filter is not usually necessary. Such a filter is exemplified in the drawings by a series connected resistor 81 and a plurality of shunt condensers 83. Naturally, an inductor may be substituted for the filter-resistor if desired.

It might be inferred from the foregoing that my invention is limited to cathode-ray tube systems wherein deflection of the ray is accomplished through the use of electromagnetic deflection coils. Such is not the case, however, since the basic principle thereof is equally as well applicable to systems wherein electrostatic forces are employed for deflection or to those of the type wherein deflection in one direction is obtained electromagnetically and in the other direction electrostatically.

For example, referring now to Fig. 2 of the drawings, if ray deflection in any given direction is accomplished by impressing a saw-tooth or sinusoidal potential across a plurality of plates 65 85 disposed in the cylindrical portion of the cathode-ray tube 1, such potentials may also be utilized to determine the working bias on the grid of the control-tube 54. For the foregoing purpose, I prefer to utilize the thermionic tube 87 having two grids 89 and 91, an equipotential cathode 93 and either a common anode 95, as illustrated, or two electrically connected anodes, one for each grid. A source 96 of anode and biasing potential is of course provided. The 75

5 grids are coupled to the ray-deflection plates through stopping condensers 87 and 89, respectively, and the device is provided with an output, or self-bias resistor 101 around which a reasonably large capacitor 103 is connected.

10 The self-bias resistor is included in the input circuit of the control tube, the connections being such that the potential across it "bucks" the static negative potential on the grid. As is well known to those skilled in the art, the average plate current from a thermionic device which obtains its bias from a self-bias resistor is substantially constant although it does increase slightly in response to the presence of grid excitation.

15 By careful adjustment, the space current in the excited condition may be made to override the static negative potential on the grid of the control-tube and the system functions in substantially the same manner as the system exemplified 20 by Fig. 1.

It should be apparent from the foregoing that my improved protective system has many advantages. If either of the deflection generators fails, the beam is immediately cut off and this 25 action also takes place if any of the connections between the generators and the deflecting coils or plates should break. Furthermore, should the control tube be deprived of positive biasing potential by failure of any element in the protective 30 devices per se, the relay will immediately drop out to notify the operator that repairs should be made.

Although I have chosen several specific embodiments of my invention for purposes of illustration, many other obvious modifications will be 35 apparent to those skilled in the art. My invention, therefore, is not to be limited except insofar as is necessitated by the prior art and by the spirit of the appended claims.

40 I claim as my invention:

1. In combination, a cathode ray tube having a fluorescent screen, means within the tube for developing a cathode ray and directing it toward the screen, means for deflecting the ray across 45 the screen according to a pre-determined recurrent pattern, a ray-accelerating anode within the tube, connections for supplying a potential to the anode and means for depriving the anode of potential and connecting it to ground upon failure of the ray-deflecting means.

50 2. In combination, a cathode ray tube having a fluorescent screen, means within the tube for developing a cathode ray and directing it toward the screen, means for deflecting the ray across 55 the screen according to a pre-determined pattern, means for deriving a unidirectional potential from the ray-deflecting means, connections for supplying anode potential to the tube and means responsive to said unidirectional potential for determining the continuity of said connections.

60 3. In combination, a cathode ray tube having a fluorescent screen, means within the tube for developing a cathode ray and directing it toward the screen, means for deflecting the ray across 65 the screen according to a pre-determined pattern,

connections for supplying anode potential to said tube, switching means included in said connections and means responsive to the energization of said ray-deflecting means for determining the operation of said switching means.

4. In combination, a cathode ray tube having a fluorescent screen, means within the tube for developing a cathode ray and directing it toward the screen, an accelerating anode interposed between the said means and the screen, means including a source of fluctuating potential for causing the ray to traverse the screen according to a pre-determined pattern, a unidirectional potential source, a thermionic tube having an output circuit including the winding of a relay, a movable armature and a fixed contact associated with the relay winding, connections whereby the armature and the contact connect the unidirectional potential source to the accelerating anode upon energization of the relay winding, means for normally biasing the thermionic tube negatively to substantially the cut-off potential, means for deriving a unidirectional potential from the source of fluctuating potential, and connections for utilizing the derived unidirectional potential to nullify the said normal negative bias whereby, when the ray is being deflected across the screen the anode is supplied with potential and potential is removed therefrom upon failure of the fluctuating potential supplying means.

5. The invention set forth in claim 4, characterized in that the unipotential deriving means includes a thermionic tube and additionally characterized in that connections are provided whereby cathode heating potential may be applied to said tube and to the biased thermionic tube from the same potential source.

6. In a cathode ray tube system, a source of fluctuating potential for causing a cathode ray to be deflected in one direction, another source of fluctuating potential for causing the ray to be deflected in another direction, a cathode ray tube having an electron emissive cathode, an accelerating anode and a fluorescent screen, a thermionic tube, means for normally biasing the thermionic tube negatively to substantially the cut-off potential, a source of unidirectional potential, means responsive to space current in said thermionic tube for establishing a connection between the accelerating anode and the unidirectional potential source, means responsive to absence of current in said tube for establishing a connection between the accelerating anode and the cathode, means for deriving unidirectional potentials from each fluctuating potential source and connections whereby said unidirectional potentials are utilized conjointly to nullify the normal negative bias applied to the thermionic tube whereby, when the ray is being deflected according to a predetermined pattern potential is applied to the accelerating anode and when deflection according to said pattern ceases the said anode is connected to said cathode to prevent the cathode ray from causing damage to the fluorescent screen.

ROBERT R. GOODRICH.
